UNITED STATES PATENT OFFICE.

ADOLPH T. JOHANSON, OF CHICAGO, ILLINOIS, ASSIGNOR TO MILTON E. PAGE, JR.,
ADOLPH T. JOHANSON, AND CHRISTOPHER M. PAGE, ALL OF CHICAGO, ILLINOIS,
AS TRUSTEES FOR AABALL MANUFACTURING COMPANY, A COMMON LAW TRUST.

AIR PREHEATER FOR OIL BURNERS.

Application filed May 21, 1924. Serial No. 714,786.

This invention pertains to improved and novel means for supplying air to a burner, such as an oil-burner, and preferably, but not restrictedly, one of the rotary type, wherein the fuel mixed with air is discharged under the action of centrifugal force in consequence of which the fuel is well subdivided and intermixed with the air.

10 The present improvement relates more particularly to means for supplying heated air to the gases after they have left the burner, and of course before they have been wholly consumed.

15 The air is not only heated by the new structure but the furnace as a whole is protected from becoming induly or inefficiently heated and the fuel is burned more effectively and economically.

20 One aim and purpose of the invention is to provide a construction of this character which is simple in structure, which is economical to produce, which may be easily installed and removed from the furnace, and 25 which performs its functions in a satisfactory and approved manner.

To permit those acquainted with this art to fully understand the invention, both from structural and functional standpoints, in the 30 accompanying drawing forming a part of this specification, I have illustrated a furnace equipped with one of the new structures, the single view of the drawing being a central vertical section of fragmentary 35 character.

In other words, the picture presents only a portion of the furnace but is sufficient for the purposes of illustrating the particular invention in question.

40 The furnace of this illustration may be of any usual or suitable design, but in the present instance, I have depicted a simple one of upright, cylindrical form having an outer, double-wall water-jacket 10.

45 Inside of such furnace and bearing on an appropriate base or foundation, not shown, are a plurality (three in the present instance) of upright posts or legs 11, 11 resting on which is a dish-shaped metal shell 50 12 desirably made in a plurality of sections bolted together at 13.

Near the top of its outside curved surface, such shell or wall member has an outstanding flange 14 provided for the purpose

of supporting a horizontal ring or annular plate 15 closing the space between the round member 12 and the inner wall of the encasing or enclosing water-jacket.

The top of the ring plate 15 is covered with any suitable heat-insulating material 60 16 such as fire clay or its equivalent.

At its center, this upper shell or wall member has a round aperture 17 and outwardly beyond the margin of this hole, the curved plate has an annular depression 18 65 adapted to catch any oil from the burner and drain it away by means not shown.

A smaller, dish-shaped shell or wall member 19, made in sections if desired, is supported from the upper member 12 and 70 spaced below the latter by means of screws 20, 20 fastening the parts together and extended through apertured spacing lugs 21 rising from the top face of such lower member.

As is clearly shown, this lower, depending shell or wall is of less diameter than its companion or complementary upper shell or wall, but this need not necessarily be so as will be readily appreciated.

These cooperating upper and lower shells or walls are disposed concentrically and the under one has a central round hole 22 in register with, but of less size than, the corresponding aperture in the upper member.

An annular or circular ring-member 23 has a flange 24 outstanding from its lower margin, the outer part thereof resting on the lower shell, the under surface of such flange conveniently and desirably having a circular bead or rib 25 to maintain the member 23 in central position by coaction with the margin of the hole 22.

The upright cylindrical wall of the main body of the part 23 is of appreciably less 95 diameter than that of the holes or apertures 22 and 17 and it extends or projects up through the hole 17 and some distance above it, its top having an outstanding, horizontal, circular flange 26 of a diameter substantially 100 greater than that of the opening 17.

Thus it will be observed that these three associated elements 12, 19 and 23, the latter with its upper and lower flanges, form a circular, downwardly-directed passage 105 between the two shells which joins with an upright annular passage through the aperture 17 formed by the body 23 and that such

vertical passage is equipped with a horizontal deflector 26 which causes the air flowing upwardly through such annular flue to be discharged outwardly above the shell 12 which swerves or directs it gently upwardly due to its dish-shape.

An oil-burner 27 fixed on a rapidly-revolving, vertical shaft 28 is positioned inside of the ring 23 projecting upwardly beyond the 10 ring as is clearly depicted.

This round, slightly-tapered burner is of general pail shape, and has a top cover-plate 29 spaced slightly above its upper, circular edge forming a round discharge 15 nozzle or orifice 30.

The liquid fuel, such as oil, is fed up into the burner in any convenient and satisfactory manner through the bore of shaft 28 which is hollow, and air is admitted into the 20 interior of the burner to mix with the fuel through the perforations 31 in its bottom wall.

The particular structural characteristics of this burner form no part of the present 25 invention except to the extent in which the air is supplied thereto to carry on the combustion of the fuel.

Another supply of air flows up through the ring 23 around the burner and mixes 30 directly with the mixture delivered through its round discharge opening, as soon as such delivery occurs.

As the partially-consumed mixture travels outwardly away from the rapidly revolving burner from which it is expelled under the action of centrifugal force, it becomes intermixed with the heated air which flows up through the tortuous conduit previously outlined formed by the two shells and the ring member, such air abstracting heat from the metal parts with which it comes in contact, thus desirably being raised in temperature and maintaining the elements of the furnace from becoming unduly heated.

It will be understood, therefore, that the 45 burner has three supplies of air, one directly into the burner itself, a second immediately outside of and adjacent to the discharge opening of the burner, and a third at some 50 distance from the burner, such arrangement of parts bringing about such distribution of the air assuring a complete and efficient combustion or consumption of the fuel.

The several elements of the structure are 55 so made and associated together that they can be readily and easily installed in a furnace and they can also be removed with facility and dispatch.

The ring member can be lifted up or 60 withdrawn through the hole in the upper shell, and the two shell members may be put in place or taken out without difficulty or loss of time.

Many minor mechanical changes may be incorporated in the structure illustrated and

described without departure from the substance and essence of the invention as defined by the appended claims, or, stated somewhat differently, the invention is susceptible of a variety of embodiments differing somewhat in structural characteristics, but all incorporating the fundamental principles of the invention.

I claim:

1. In a construction of the character described, the combination of a plurality of upright legs, an upper centrally-apertured downwardly-dished shell resting and supported on said legs, a second lower, centrally-apertured downwardly-dished shell 70 spaced below and supported from said upper shell, a ring inside of the apertures of said shells supported on said lower shell, spaced inwardly away from the margin of the aperture of said upper shell, and having an outwardly-extended flange above said upper shell, and a fuel-burner having a discharge opening above said ring, whereby air flowing inwardly between said shells is caused to flow upwardly and outwardly 85 above said upper shell where it mixes with the gases issuing and at some distance from said burner, such air being preheated by said shells during its passage through the 90 conduit specified.

2. In a construction of the character described, the combination of a plurality of upright legs, an upper centrally-apertured downwardly-dished shell resting and supported on said legs, a second lower, centrally-apertured downwardly-dished shell 100 spaced below and supported from said upper shell, a ring inside of the apertures of said shells supported on said lower shell, spaced inwardly away from the margin of the aperture of said upper shell, and having an outwardly-extended flange above said upper shell, a fuel-burner having a discharge opening above said ring, means to admit air to the interior of said burner, and means to 105 admit air between the burner and said ring to commingle with the gases as they issue from the burner, whereby air flowing inwardly between said shells is caused to flow upwardly and then outwardly above said 110 upper shell where it mixes with the gases issuing and at some distance from said burner, such air being preheated by said shells during its passage through the 115 conduit specified.

3. In a construction of the character described, the combination of a plurality of upright legs, an upper centrally-apertured downwardly-dished shell resting and supported on said legs, a second lower, centrally-apertured downwardly-dished shell 125 spaced below and supported from said upper shell, a ring inside of the apertures of said shells, supported on said lower shell, spaced inwardly away from the margin of the aper-

ture of said upper shell, and having an outwardly-extended flange above said upper shell, a fuel-burner having a discharge opening above said ring, means to admit air to the interior of said burner, whereby the air flowing inwardly between the shells is caused to flow upwardly and then outwardly above said upper shell where it mixes with the gases issuing and at some distance from said burner, such air being preheated by said shells during its passage through the conduit specified.

4. In a construction of the character described, the combination of a plurality of upright legs, an upper centrally-apertured downwardly-dished shell resting and supported on said legs, a second lower centrally-apertured downwardly-dished shell spaced below and supported from said upper shell, a ring inside of the apertures of said shells, supported on said lower shell, spaced inwardly away from the margin of the aperture of said upper shell, and having an outwardly-extended deflector above said upper shell, a rotary fuel-burner having a discharge opening above said ring, and means to admit air between said burner and said ring to unite with the gases as they immediately issue from the burner, whereby the air flow-

ing inwardly between said shells is caused to flow upwardly and then outwardly above said upper shell where it mixes with the gases issuing and at some distance from said burner, such air being preheated by said shells during its passage through the conduit specified.

5. In a structure of the character described, the combination of an upper shell having an aperture therethrough, a lower shell spaced downwardly away from said upper shell having a smaller aperture therethrough in register with said upper aperture, a hollow ring member having an outstanding flange of less size than said upper aperture and resting on said lower shell around the margin of its aperture and having also an outstanding deflector flange above and of greater size than said upper aperture, and a burner having its discharge orifice above said deflector flange, said shells and ring member forming an air preheating conduit which delivers its air to the gases issuing from and at some distance outwardly from said burner orifice.

In witness whereof I have hereunto set my hand.

ADOLPH T. JOHANSON.
